(57) **CLAIM**

The ornamental design for a mowing knife, as shown and described.

DESCRIPTION

FIG. 1 is a perspective view of a mowing knife showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof, configured with a first handle;

FIG. 9 is a perspective view thereof, configured with a second handle;

FIG. 10 is a sectional view showing a section taken from the position A-A in FIG. 2; and,

FIG. 11 is a sectional view showing a section taken from the position B-B in FIG. 2.

The broken lines depict portions of the mowing knife that form no part of the claimed design.

The dot-dash broken lines in FIG. 2 indicate the section position and form no part of the claimed design.

1 Claim, 8 Drawing Sheets
